UNITED STATES PATENT OFFICE.

RUDOLPH F. JAEKEL, OF MILWAUKEE, WISCONSIN.

WINDOW CONSTRUCTION.

1,185,406.

Specification of Letters Patent. Patented May 30, 1916.

Application filed May 29, 1915. Serial No. 31,179.

To all whom it may concern:

Be it known that I, RUDOLPH F. JAEKEL, a citizen of the United States, residing at Milwaukee, in the county of Milwaukee and

5 State of Wisconsin, have invented certain new and useful Improvements in Window Construction, and I do hereby declare the following to be a full, clear, and exact description of the invention, such as will enable others skilled in the art to which it ap-

10 pertains to make and use the same.

This invention relates to window constructions, and the primary object of the invention is to provide a novel form of window 15 construction, which will eliminate the necessity of the employment of storm windows, separate screens, and further to provide a window construction wherein the screen will be moved with the movement of the sliding window sashes, for always having the open 20 section of the window properly screened, for preventing the passage of flies or other insects therethrough.

Another object of this invention is to provide a novel form of guiding slides, for 25 guiding the travel of the screens, which are provided with enlargements formed therein; and further to provide means for detachably connecting the screens to the lower rail 30 of the lower sash and the upper rail of the upper sash, whereby the screens may be easily and conveniently detached from connection to the sashes, when the fastening means are positioned in alinement with the 35 enlarged portions of the guides.

Another object of this invention is to provide a novel means for attaching the weights 40 to the windows, for holding the screens taut at all times, and for winding the screens upon rollers, upon the closing of the window.

A still further object of this invention is to provide means for holding the screen retaining rolls against movement, when desired, and for connecting the weights direct 45 to the window sashes, for counterbalancing the weights of the sashes during their movement, when it is desired to use the sashes independently of the screens.

With the foregoing and other objects in 50 view this invention consists in such novel features of construction, combination and arrangement of parts as will be hereinafter more fully described, illustrated in the accompanying drawings and claimed.

55 In describing the invention in detail ref-

erence will be had to the accompanying drawings wherein like characters designate like and corresponding parts throughout the several views, and in which:—

Figure 1 is a side elevation partially in section of the improved window construction, Fig. 2 is a vertical section through the window construction, Fig. 3 is a sectional view on the line 3—3 of Fig. 1, Fig. 4 is a cross section on the line 4—4 of Fig. 1, 60 Fig. 5 is a detail perspective view of one corner of one of the sashes, Fig. 6 is a detail perspective view of the manner of detachably connecting the screens to the sashes, Fig. 7 is a side elevation of one of the metallic guides carried by the window frame, and Fig. 8 is a fragmentary plan view of the window construction.

Referring more particularly to the drawings, 1 designates the window construction 75 as an entirety, which has a lower outer sill 2, to which is detachably connected, by means of screws 3, the inner lower sill 4. The upper sill 5 of the window frame has the front or inner upper sill 6 secured thereto 80 by suitable fastening devices, illustrated at 7, and its front edge forms a molding, dividing the side members 7 of the casing from the cap 8, running back to where the upper sash closes, and replaces the ordinary divid- 85 ing rail, as well as eliminating the ordinary inside stop along the top of the window.

The cap 8 has a plurality of dowel pins 9 secured thereto, which extend into openings 10 formed in the sides 7 of the window 90 frame, for detachably connecting the cap 8 to the frame construction 1 proper. The front sill 4 is provided with a recess indicated at 10, which relieves the lower end of the side members 7 of the casing. A strip 11 95

of molding is secured to the wall of the building, below the lower edge of the window opening, and it is provided with slots extending inwardly from its ends, which receive the locking members 12. The locking members 12 are pivotally connected to the front boards 13, and have their lower ends curved, as is shown at 14, for insertion beneath the lower rounded edge of the molding for securely holding edge of the front boards 105 13 attached to the molding and the wall for forming the casing. The upper edge of the front boards 13 is inserted between the forward inner edge of the lower outer sill 2, and the inner edge of a strip 15 of molding, 110

which is secured to the under surface of the inner sill 4, as is clearly shown in Fig. 3 of the drawings.

The window construction 1 has a pair of 5 slidable sashes 20 and 21 mounted therein, as is ordinary in window constructions. The sashes 20 and 21 are provided with longitudinally extending cut-out portions 22 and 23 respectively, formed in their opposite vertical edges, which receive substantially U-shaped guiding strips 24 and 25. The guiding strips 24 and 25 are inserted in the side members 7 of the window frame, and protrude a short distance outwardly beyond the outer surface of the same, for insertion into the recesses 22 and 23.

The lower sash member 20 has a hook bar 26 secured to the under surface of the lower cross rail of the same. The hook bar 26 is 20 formed of a sheet of metal, which is bent downwardly, as is shown at 27, to form a hook, which is provided for engagement with a hook 28. The hook bar 28 is also formed of sheet metal bent to form a hook section 29 which is provided for engagement with a hook section 27 of the hook bar 26, and it is secured to the upper edge of a screen 30. The screen 30 is rolled about a roller 31, which is positioned in the housing 30 32 formed beneath the sill 2, and is rotatably carried by open bearings 33. The edges of the screen 30 travel in the open faces of the U-shaped guide strips 24 and 25, which are seated in recesses formed in the side members 7. The roller or drum 31 has one end of a weight cord or chain 35 connected thereto, which extends upwardly through the lower sill 2, and passes about a pulley 36. The pulley 36 is carried by the window casing, and the cable 35 passes over this pulley, and downwardly about a pulley 37. The pulley 37 has the ordinary type of counterbalancing weights 38 attached thereto, and hanging pendently therefrom. The cable 35 40 passes from the pulley 37, upwardly about a pulley 38, and downwardly therefrom, being connected to one of the side rails of the sash 20, a short distance downwardly from the upper end of the same, as is clearly 45 shown at 39 in Fig. 1 of the drawings. By attaching the weight 38 to the cable 35, and passing the cable about the various pulleys, and connecting it to the drum 31 and the upper edge of the window sash, as has been heretofore described, it will be seen that the 50 weights will tend to draw the end of the cord which is attached at 39 to the window sash, downward, and the lower end of the cable, which is wound about the drum, upward, thus drawing the roller and sash in opposite directions, keep the screen under tension, and counterbalancing the sash at the same time. As the sash is raised and lowered, the counterbalancing weight 60 remains in the same place.

The drum or roller 31, has a plurality of eye bolts 40 secured thereto at spaced intervals about its circumference, and positioned outwardly of the edge of the screen 30. The eye bolts 40 are provided for receiving the 70 lower end of a rod 41, which is connected to a cross pin 42. A button 43 is connected to the outer end of the pin 42, and projects outwardly through the side member 7 of the casing, being positioned for convenient 75 engagement by the thumb or finger of a person, for sliding the rod 41 within the slot 44, in the member 7, for moving the pin 41 into or out of engagement with one of the eyes 40, thereby arresting or permitting rotation of 80 the drum, as desired. A spring may be mounted in the opening 44 for holding the pin 41 in an upward position and out of engagement with one of the eyes 40.

When it is desired to operate the sash 85 independent of the screen, the sash is moved to a point opposite of enlargements 25^a, which are formed in the U-shaped members 25 and extend toward the outside of the metallic slide or guides 25. The button 43 is 90 then pushed down, for moving the pin 40 into engagement with one of the eyes 41, which holds the roller or drum 31 stationary. By further downward movement of the sash, the screen 30 becomes slack, and as the 95 hook bar 28 passes through the enlargement 25^a, it automatically becomes disconnected from the hook bar 26, and the screen may be pushed downwardly into the housing. The metallic guides 25 extend downwardly 100 through the lower sill 2, and the edges of the screen rest therein, for properly seating the screen within its bounds. The opening in the sill 2, through which the screen passes, is narrow enough to prevent the hook bar from 105 passing therethrough. The roller 31 is mounted, so that the screen will pass tangentially of the same, substantially in alignment with a line drawn along the center of the lower rail of the sash 20.

The upper sash 21 has a hook bar 45 secured to its upper end, which is constructed identical with the hook bar 26. The hook bar 45 is provided for attachment with a hook bar 47, which is secured to the lower 110 end of a screen 48. The screen 48 is wound about a roller or drum 49, which is rotatably mounted in the cap 8, and supported by open bearings 50. The screen 48 passes upwardly through an opening 51', which is 115 formed in the top sill 5, and its edges travel in the U-shaped metallic guides 24, which are carried by the side members 7 of the casing 1. The drum or roller 49 has a plurality of eye bolts 51 secured thereto at 120 spaced intervals about its circumference, which eyes are provided for receiving the upper end of a pin 52. The pin 52 is bent upon itself, as is clearly shown in dotted lines in Fig. 3 of the drawings, and it has 13

a button 53 mounted upon its outer end, which is slidably mounted in an opening 54 formed in one of the side members 7. The rod 52 is provided for having its upper end 5 inserted into one of the eyes of the eye bolts 51, for arresting rotation of the drum 49, as will be hereinafter more fully described. The cross-piece 55 has an opening 56 extending therethrough, which has its lower 10 end countersunk, as is shown at 57, for receiving a ring 58, which is mounted upon one end of a cable or chain 59. The cable or chain 59, extends upwardly from the recess 56, and travels over a grooved pulley 15 60. The grooved pulley 60 is carried by the top of the cap 8, and is positioned diagonally, for carrying the cable across the drum 49. The cable 59 extends downwardly from the pulley 60, and about a 20 pulley 61, which has a balancing weight 62 carried thereby, and depending therefrom. The cable then extends upwardly from the pulley 61 and is wound about the roller or drum 51, in an opposite direction, having 25 its end secured to the drum. The pulley 60 is diagonally bent into the top of the frame, so that the cable will be brought from one side of the roller to the opposite side, and also for bringing its end which carries the 30 ring 58, in direct line with the upper sash. It is evident that, when the sash is pushed up, the weight will revolve or rotate the roller or drum 51, and wind the screen thereon, during the downward course or 35 movement of the weight. It is further clear that the weight pulling in one direction, and the weight of the sash in the other, will bring about a state of tension, as the screen is rolled or unrolled, while the sash 40 is being counterbalanced when opened, or held in a closed position when shut.

When it is desired to use the sash independently of the screen, the sash is brought to a position to aline with the enlargements 45 which are formed in the bar 24, and by the provision of the enlargements, the hook bar 47 may be disconnected from the hook bar 45, after the rod 52 has been moved for insertion into one of the eyes of the eye bolts 50 51, for arresting rotation of the drum. Upward movement of the sash will cause the screen to get slack after the roller has been locked against rotary movement, and when the sash is brought into alinement with the 55 enlarged portions of the U-shaped bars, it is brought to a standstill, and a slight downward movement of the sash will cause the hook bars to become unhooked, so that the screen can be moved upward into the housing. When the screen is unhooked from 60 the sash, the latter is deprived of its counterweight, and this is overcome, by pulling the cable downwardly through the opening 56, and attaching the ring 58 to a hook 66, 65 which is secured to one side of the top rail

of the upper sash 21, adjacent its upper edge, which will directly connect the sash to the counterbalancing weight 62.

The guides 24 and 25, projecting out of the sides 7 of the casing 1, into the side 70 rails of the sashes, and also the hook bars which are inserted into the openings formed in the upper and lower sills, through which the screen passes, when the sashes are in a closed position, form a substantially 75 weather-tight window, eliminating the necessity of the employment of separate storm windows, or weather stripping of the windows in windy or cold weather.

The lower check rail 70 of the upper sash 80 21, has a pair of metallic guides 71 secured thereto, which slidably support a metallic plate 72. The metallic plate 72 extends across the full width of the bottom window light, and is provided for keeping the opening between the window light and the lower sash rail 70 closed sufficiently to keep out flies, and also form closures for the openings between the check rails, when the window is closed, and keep the wind from penetrating through the same. The check rail 70 has a catch 72' secured thereto in the center of the same, which engages the inner curved edge of the plate 72 and holds the same in place. 95

From the foregoing description taken in connection with the accompanying drawings the advantages of construction and of the method of operation of the improved window construction will be readily apparent 100 to those skilled in the art to which this invention appertains and, while in the foregoing description, the principle of the operation of this invention has been described together with various features of construction, it is to be understood that certain minor features of construction, combination and arrangement of parts may be altered to suit practical conditions provided such alterations are comprehended within the 110 scope of what is claimed.

What is claimed is:—

1. In a window construction, a window casing, upper and lower sashes slidably carried by said casing, the sides of said sashes being provided with longitudinally extending grooves, vertically positioned substantially U-shaped metallic members carried by said casing and extending into said grooves, screens connected to said sashes for movement therewith, said screens having their edges positioned within said U-shaped metallic members. 120

2. In a window construction, a window casing, upper and lower sashes slidably carried by said casing, upper and lower caps carried by said casing, drums rotatably mounted within caps, screens wound upon said drums and having their free ends detachably connected to the upper and lower 125

edges of the upper and lower slidable sashes respectively for movement with the sashes for screening the opening formed by the opening of the sashes, a plurality of eye-bolts carried by said rollers, rods slidably carried by said casing and adapted for insertion through certain of said eye-bolts for arresting rotation of said drums.

3. In a window construction, a window 10 casing, upper and lower sashes slidably carried by said casing, upper and lower caps carried by said casing, drums rotatably mounted within said caps, screens wound upon said drums and having their free ends 15 detachably connected to the upper and lower edges of the upper and lower slidable sashes respectively for movement with the sashes for screening the openings formed by the opening of the sashes, vertically positioned 20 substantially U-shaped metallic members carried by said casing, said sashes being provided with vertically extending grooves, said metallic members extending into said grooves, a screen having their edges extending into said vertically positioned substantially U-shaped metallic members.

4. In a window construction, a window 25 casing, upper and lower sashes slidably carried by said casing, drums rotatably supported by said casing above the upper edge of said uppermost sash and below the lower edge of said lower sash, screens wound upon said drums, metallic hook bars secured to the upper edge of said upper sash and the lower 30 edge of said lower sash, hook bars secured to the free ends of said screens and being provided for detachable connection with said sash carried hook bars, sash cords connected to said sashes, counterbalancing weights carried by said sash cords, said sash cords being 35 connected to said drums for holding said screens taut upon movement of said sashes, a plurality of eye-bolts carried by said drums, rods carried by said casing and adapted for insertion through certain of said 40 eye-bolts for arresting rotation of said drums when said screens are detached from connection with the sashes.

5. In a window construction, a window 45 casing, upper and lower sashes slidably carried by said casing, drums rotatably supported by said casing above the upper edge of said uppermost sash, and below the lower edge of said lower sash, screens wound upon 50 said drums, metallic hook bars secured to the upper edge of said upper sash and the lower edge of said lower sash, hook bars secured to the free ends of said screens and being provided for detachable connection 55 with sash-carried hook bars, sash cords connected to said sashes, counterbalancing weights carried by sash cords, said sash cords being connected to said drums for holding said screens taut upon the movement 60 of said sashes, and means for holding said 65

drums against rotation, when said screens are detached from connection to said sashes.

6. In a window construction, a window 70 casing, upper and lower sashes slidably carried by said casing, substantially U-shaped guiding bars carried by said casing and projecting outwardly therefrom, said sashes being provided with longitudinally extending recesses formed in the outer surfaces of the side rails thereof, said U-shaped 75 guiding members extending into said sash-carried recesses, a roller rotatably carried by said casing above the upper end of said upper sash, a roller rotatably carried by said casing below the lower end of said lower sash, screens wound upon said rollers, said screens being adapted for detachable connection to said sashes, the edges of said screens being seated between the legs of said U-shaped guide members, and enlargements 80 formed upon said U-shaped guide members for permitting of the disconnection between said screens and said sashes.

7. In a window construction, a window 85 casing, upper and lower sashes slidably carried by said casing, substantially U-shaped guiding bars carried by said casing and projecting outwardly therefrom, said sashes being provided with longitudinally extending recesses formed in the outer surfaces of 90 the side rails thereof, said U-shaped guiding members extending into said sash-carried recesses, a roller rotatably carried by said casing above the upper end of said upper sash, a roller rotatably carried by 95 said casing below the lower end of said lower sash, screens wound upon said rollers, said screens being adapted for detachable connection to said sashes, the edges of said screens being seated between the legs of said U-shaped guide members, enlargements 100 formed upon said U-shaped guide members for permitting of the disconnection between said screens and said sashes, sash cords connected to said sashes and said rollers, counterbalancing weights carried by said sash cords for balancing the weight of said sashes 105 and holding said screens taut when unwound from said rollers.

8. In a window construction, a window 110 casing, upper and lower sashes slidably carried by said casing, substantially U-shaped guiding bars carried by said casing and projecting outwardly therefrom, said sashes being provided with longitudinally extending 115 recesses formed in the outer surfaces of the side rails thereof, said U-shaped guiding members extending into said sash-carried recesses, a roller rotatably carried by said casing above the upper end of said upper sash, a roller rotatably carried by said casing below the lower end of said lower sash, screens wound upon said rollers, said screens being adapted for detachable connection 120 to said sashes, the edges of said 125 screens being seated between the legs of said 130

screens being seated between the legs of said U-shaped guide members, enlargements formed upon said U-shaped guide members for permitting of the disconnection between 5 said screens and said sashes, sash cords connected to said sashes and said rollers, counterbalancing weights carried by said sash cords for balancing the weight of said sashes and holding said screens taut when 10 unwound from said rollers, and means for arresting rotation of said rollers when the screens are disconnected from said sashes for permitting said balancing weights to act independent of the screens for counterbalancing said sashes. 15

9. In a window construction, a window casing, upper and lower sashes slidably carried by said casing, substantially U-shaped guiding bars carried by said casing and projecting outwardly therefrom, said sashes being provided with longitudinally extending recesses formed in the outer surfaces of the side rails thereof, said U-shaped guiding members extending into said sash carried 20

recesses, a roller rotatably carried by said casing above the upper edge of said upper sash, a roller rotatably carried by said casing below the lower edge of said lower sash, screens wound upon said rollers, said screens being adapted for detachable connection to said sashes, the edges of said screens being seated between the legs of said U-shaped guiding members, enlargements formed upon said U-shaped guide members 25 for permitting of the disconnection between said screens and said sashes, a plurality of eye-bolts carried by said rollers, rods slidably carried by said casings and adapted for insertion through certain of said eye-bolts for arresting rotation of said drums when 30 said screens are disconnected from said sashes. 35

40

In testimony whereof I affix my signature in presence of two witnesses.
